Primary Examiner—Jeffrey D Asch*Assistant Examiner*—Bridget L Eland(74) *Attorney, Agent, or Firm*—St. Onge Steward Johnston & Reens LLC(57) **CLAIM**

The ornamental design for a retractor with optic shaft, as shown and described.

DESCRIPTION

FIG. 1 is a right side perspective view of a retractor with optic shaft in accordance with the new design;

FIG. 2 is a right side elevation view thereof;

FIG. 3 is a left side elevation view thereof;

FIG. 4 is a top elevation view thereof;

FIG. 5 is a bottom elevation view thereof;

FIG. 6 is a front elevation view thereof; and,

FIG. 7 is a rear elevation view thereof.

The broken line showing in FIGS. 1 and 7 is included for the purpose of illustrating portions of the article that form no part of the claimed design.
